Primary Examiner — Mimosa De(74) *Attorney, Agent, or Firm* — Leanne Taveggia Farrell; Westman, Champlin & Koehler, P.A.(57) **CLAIM**

The ornamental design for a chair, as shown and described.

DESCRIPTION

FIG. 1 is a perspective view of a chair showing our new design;

FIG. 2 is a side view thereof, the opposing side being a mirror image;

FIG. 3 is a front view thereof;

FIG. 4 is a back view thereof;

FIG. 5 is a top view thereof; and,

FIG. 6 is a bottom view thereof.

The broken lines shown in the drawings are included for purposes of illustrating portions of the chair and form no part of the claimed design.

1 Claim, 6 Drawing Sheets(56)
